Primary Examiner — Cary M Robinson*Assistant Examiner* — Emily Anna Saunders(74) *Attorney, Agent, or Firm* — Birchwood IP(57) **CLAIM**

The ornamental design for a bubble machine, as shown and described.

DESCRIPTION

FIG. 1 is a front, right and top perspective view of the bubble machine, showing my new design;
FIG. 2 is a rear, left and bottom perspective view thereof;
FIG. 3 is a front view thereof;
FIG. 4 is a rear view thereof;
FIG. 5 is a left side view thereof;
FIG. 6 is a right side view thereof;
FIG. 7 is a top plan view thereof;
FIG. 8 is a bottom plan view thereof; and,
FIG. 9 is an enlarged view of the area labeled 9 in FIG. 1. The broken lines in the drawings illustrate portions of the bubble machine that form no part of the claimed design. The dot-dash broken lines encircling portions of the bubble machine in FIG. 1 and illustrated in enlarged views in FIG. 9 form no part of the claimed design.

1 Claim, 9 Drawing Sheets(56)
